UNITED STATES PATENT OFFICE

JOHN NEWBERRY REYNOLDS, OF GREENWICH, CONNECTICUT, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,308,867.

Specification of Letters Patent.

Patented July 8, 1919.

Application filed November 2, 1917. Serial No. 199,862.

To all whom it may concern:

Be it known that I, JOHN NEWBERRY REYNOLDS, a citizen of the United States, residing at Greenwich, in the county of Fairfield and State of Connecticut, have invented certain new and useful Improvements in Telephone-Exchange Systems, of which the following is a full, clear, concise, and exact description.

This invention relates to automatic switching apparatus for telephone exchange systems, and particularly to apparatus including brush mounting and operating means whereby a large number of lines are quickly and efficiently served with a minimum expenditure of time and wear on the apparatus. This apparatus is especially adapted to use in connection with multiple contact banks of the type shown and described in my copending application, Serial No. 158,190, filed March 29, 1917, telephone exchange systems. When used in connection with the contact bank described in this prior application, a brush is moved up to the level desired and then moved in across the line terminals either in a hunting or directed movement. The mechanism involved in the present invention is adapted to be used with a plurality of groups of lines of the type set forth in the above mentioned application, so that it becomes necessary first to select a brush serving the desired group of lines, which, when properly operated, will be moved up to the desired level and then in as just described to contact with one of the lines in that level. To effect this, means are provided whereby the calling party, through well-known electrical devices, operates a shaft connected with that which carries the brush holders. This second shaft carries a plurality of latching members thereon, each arranged at a level corresponding to the spacing of the brushes used and at intervals around this shaft. At the second shaft is rotated a given number of steps a particular latching member is brought into position to engage with a desired brush holder to move the selected brush outwardly into engagement with the contacts of the selected level.

Another feature of the invention resides in a novel arrangement of parts whereby

the latch means is restored to normal at the end of the operation.

The invention is best illustrated in the drawings, in which Figure 1 is an elevation of the switch operating means;

Fig. 2 is a section on the line 2—2 of Fig. 1.

Fig. 3 is a view, partly in section, taken on the line 3—3 of Fig. 1; Fig. 4 is a view, partly in section, taken on line 4—4 of Fig. 1; Fig. 5 is an elevation of the upper part of the switch shaft carrying the brushes and their holders; Fig. 6 is a view of the inner latch-carrying shaft; Fig. 7 is a view, partly in section, taken on the line 7—7 of Fig. 1; Fig. 8 is a section, taken on line 8—8 of Fig. 9; Fig. 9 is a view, partly in section, taken on line 9—9 of Fig. 5; and Fig. 10 is a diagram of the circuits involved in the operation of the switch in accordance with my invention.

As illustrated in the drawings, the bank contacts 1, 1 are of the type clearly described in my application, Serial No. 158,190, filed March 29, 1917, telephone exchange systems.

The brush operating mechanism, which is illustrated in detail in Figs. 1 to 9, inclusive, is designed to first select the brush serving the desired group of lines, then to move the brushes step by step to the several levels of the contact bank until the desired level is reached and then transversely thereof to certain contacts of the level. As shown in the drawing 2 designates two of a plurality of brushes, each mounted upon a carriage 3, which is secured to a hollow shaft 4. The shaft 4 is slidable in guide members 5 and 6 and secured to a frame plate 8. Located adjacent to the shaft 4 is a toothed bar 9, adapted to be engaged by a stepping pawl 10, carried by an armature 11 of a stepping magnet 12. The toothed bar 9 is supported by collars 13 and 14, which are slidable upon the shaft 4, but there is secured to the shaft 4 a spring-pressed locking member 15, adapted, in the normal position of the shaft 4 and the toothed bar 9, to engage a notch 16 in said toothed bar 9 to lock it to said shaft 4. Within and extending throughout the length of hollow shaft 4 and movable therein is a shaft 17, which, at

its lower end below shaft 4, is embraced by a sleeve 18, to which it is connected by a slot and key. Keyed to sleeve 18 is a ratchet wheel 19, to which is attached one end of a spring 20, the other end of which is fastened to a guide member 21. Ratchet wheel 19 is adapted to be acted upon by pawl 22, carried by armature 23 of rotary magnet 24. A locking pawl 25 engages the pinion 19 opposite pawl 22, pawl 25 being pivoted at 26 and held in engagement with pinion 19 by a spring 27. The pawl 25 is adapted to be released from engagement with pinion 19 by the engagement with its rear shoulder 28 of a release bar 29, carried by a collar 30 on the lower end of shaft 4, which bar 29 normally rests against the back of shoulder 28 in a position slightly off perpendicular. When drawn up with shaft 4, bar 29 assumes a perpendicular position, and, when dropped its lower end strikes shoulder 28 to release pawl 25.

The upper portion of shaft 17 is reduced in cross section just below each brush holder 25 and a slot 31 is provided in each such reduced section, each slot being cut through shaft 17 at a different angle from the other slots, so that the angle between the planes of successive slots is equal to the angle 30 through which the shaft 17 is rotated per step by rotary magnet 24. Mounted in each slot is a latch lever 32 pivoted near its upper end and provided with a hooked lower end 33, which, in its normal position remains 35 within slot 31. The upper end 34 of latch lever 32 normally projects out of slot 31 slightly. The brush mounts 37 are fastened to shaft 4 by means of set screws 38, the inner ends 38' of which project slightly into 40 the space formed between the inner wall of the shaft 4 and the reduced portion of shaft 17. As the shaft 17 is moved upwardly, it carries with it the lever 32, the upper end of which contacts with the end of set screw 38, 45 thus forcing the lower end of the lever 32 out of slot 31. Vertical slots 39 are formed in shaft 4, which are adapted to register with slots 31 in shaft 17 when slots 31 are moved into the position when the latch lever 50 is adapted to operate. Positioned near the lower end of slot 39 is the lower end of a bell-crank lever 40, mounted on the brush mount 37, the upper end of lever 40 being connected to the brush carriage 3. When 55 shaft 17 is moved up within shaft 4 and the hooked end of lever 32 is moved out of slot 31, it engages the lower end of lever 40, and any further movement of shaft 17 moves the brushes 2 out over the contacts. When the 60 shaft 17 is dropped back into normal position within hollow shaft 4, the levers 32 are returned to normal position within their slots by the engagement of the lower sloping edge 35 thereof with the lower edge 36 of the 65 opening 39 in the hollow shaft 4.

In the first movement of the apparatus in response to impulses sent through rotary stepping magnet 24, the pawl 22 will engage the pinion 19 and rotate shaft 17 to bring a particular one of the slots 31 opposite the 70 corresponding slot 39 in the shaft 4 thus positioning the levers 32 to be ready to engage the lever 40 connected to the desired brush carriage.

At the cessation of the first set of impulses 75 through the rotary magnet 24 a side-switch magnet 41 will be caused to operate. This magnet by its armature 42 and a pawl and ratchet connection 43, 44 controls the operation of cam disks 45 and 46. These cam 80 disks have two sets of surfaces, each set adapted to control a switch movement through a complete cycle of operations. Cam disk 45 operates the side-switch arm 47 by means of rollers 48, 48 and progressively 85 advances the side switch step by step. Normally, an antifriction roller 49, secured to a pivoted lever 50, rests in an opening 51 between adjacent sets of surfaces on cam disk 46. At the first deenergization of the magnet 41, the cam disk 46 will be moved one step around in the direction of the arrow, as indicated in Fig. 7, and the side-switch arm 47 will be moved from first to second positions. The opening 51, in cam disk 46, 90 however, has such a circumferential length that this movement does not affect the roller 49 but leaves it in position ready to engage the first surface of cam disk 46.

In the second movement of the apparatus 100 in response to impulses through the stepping magnet 12 the pawl 10 will engage the toothed bar 9 to move said bar 9 and the shafts 4 and 17 upwardly in steps equal in length to the distance between two successive teeth on the bar 9 until the brushes selected have been moved into a position opposite the desired level.

At the cessation of the second series of impulses which are transmitted through stepping magnet 12, the side-switch magnet 41 will again be caused to deenergize to move cam disk 45 one step and the side-switch arm 47 from second to third position. Likewise, cam disk 46 is moved forward one step 110 and a sloping cam surface 52 will be moved under roller 49 to push the lever 50 to the left, as shown in Fig. 1; at a third step of the magnet 41 a straight surface 53 will be moved under the roller 49 to hold said lever 115 50 in its outward position; at the fourth, fifth and sixth steps of cam disk 46 the roller 49 will still be on the straight surface; at the seventh step the roller will be moved to the right as shown in Fig. 1 by sloping surface 54, to release the pivoted bar 50; and at the eighth step the roller will be moved into the next open space 51. During these 120 steps of cam disk 46, cam disk 45 has been advancing side-switch arm 47 step by step 125 130

from one position to the next. When the cam disk 45 makes the eighth and last step of its cycle, the rollers 48 pass off the rear edge of cam disk 45 and swing back to starting position again, due to the weighted rear end 47' of the switch arm 47.

The second step of the magnet 41, as above set forth, brings sloping cam surface 52 under the roller 49 and moves the lever to the left as in Fig. 1. This movement of the lever 50 causes the toothed bar 9 to be released from the shaft 4 and alters the stepping distance of the brushes in a manner clearly set forth in my co-pending application, above referred to. After the toothed bar 9 has been released from shaft 4 in this well known manner, the magnet 12 receives a third series of impulses, either directed or automatic, which moves the brushes 2, transversely of the contacts. This is effected as follows:

To the upper end of bar 9 is attached a collar 14 which loosely embraces shaft 4. A set screw passes through this collar and into a slot in shaft 4 and its end rests in a circumferential groove in a collar 17 fastened to inner shaft 17 (see Fig. 2). Thus when the toothed bar 9 is now stepped up by magnet 12, the shaft 17 is carried with it. As soon as the shaft 17 starts to move, the latch lever 32 which has been selected is moved out to grip the lower end of lever 40 and thereby move the brushes, as desired.

This first step of the brush carriage 37 is sufficient to bring the brushes 2 into engagement with the first set of contacts of the selected level. The succeeding steps of the bar 9, however, which are caused by the magnet 12 will be only half the distance of those caused by the impulses of the previous series so that the subsequent movement of the brushes 2 will be only the distance between successive sets of contact surfaces. The magnet 12 is then automatically operated to move the brushes 2 into engagement with an idle set of terminals in the level selected by the second set of impulses. At the end of this hunting action, the magnet 41 will be again deenergized to cause the cam disk to make one step. During this step the straight surface 53 of the cam disk 46 will still be under the roller 49 and it has no further effect on the lever 50. This step of the magnet 41 also moves the side-switch arm 47 to the fourth position, at which time the two subscribers' lines are connected.

The parts will remain in this position with the side-switch arm 47 in engagement with the fourth position contact during the conversational period, at the end of which time the operation of making a disconnection will use the automatic operation of the magnet 41 to advance the cams 45 and 46 to releasing position. This movement of the cam 46 will move the cam surface 54

over the roller 49. The movement of the cam surface 54 over the roller 49 turns the lever 50 backwardly to the right, as viewed in Fig. 1, until a finger 55 thereon engages the finger 56 on a bracket member 57 76 pivoted on the rod 57' and which carries a holding pawl 58, normally adapted to engage the teeth of the toothed bar 9 to retain it in its elevated position. Thus the backward movement of the lever 50 carries with it pivoted bracket 56 to release the holding pawl 58 from the bar 9. This will cause the bar 9 to drop by gravity, and cause the brush carriage 3 to move outwardly assisted by spring 3' to draw the brushes 2 clear of the contact strips 1-1.

As the bar 9 moves downwardly, the shaft 4 remains locked in the manner clearly set forth in my prior application, above noted. This action carries shaft 17 down with bar 85 9 until bar 9 and shaft 4 lock together again, at which time the shaft 17 has dropped a distance sufficient to move the hooked lower end of lever 32 below the lower end of lever 40 and thus permit of their disengagement. 90 As this happens lever 32 is returned to normal by the engagement of its lower beveled edge 35 with the lower edge 36 of the slot 39. When the shaft 4 and the bar 9 reach the limit of their downward movement, the lower end of the bar 29 will strike the rear shoulder 28 of the pawl 25 to cause the same to release pinion 19, which then, under action of spring 20, moves the inner shaft 17 back to normal position. At this 100 time, the magnet 41 will again be operated to move the cam disk another step. The last step of the cam disks will bring the roller 49 into the next open space 51 of the cam disk 46 and will bring the rollers 48 105 into the next open space of the cam disk 45, whereupon the side-switch arms, due to the weight of the end 47' thereof, will be swung back to the first position.

In Fig. 10 the switch mechanism of this 110 invention is shown connected in a circuit to function as a selector, although it is obvious that the device is not limited to this specific use.

Referring to Fig. 10, A may represent a 115 calling subscriber's station, the line for which is connected with line finder terminals 111, 111, adapted to be engaged by movable contacts 112, 112. Assuming that the subscriber at station A desires connection with a subscriber, say at a substation B, the operation will be as follows: The subscriber A, upon removal of his receiver from the switchhook, will automatically have his line connected with the movable contacts 112, 125 112, in a well known way through the operation of the line finder. Following the closure of the line finder contacts, a relay 115 will be energized over a line circuit, through position 1 of the side-switch wipers 116 117, 130

controlled by the selector switch embodying the features of this invention. The energization of relay 115 will cause it to open back contact 121 and close its front contact 122 to ground, thereby completing a circuit including a slow release relay 123. Relay 123 is energized and attracts its armatures, putting ground on lead 124 through its left armature, and putting ground on the lead 138 so that, when said switch wiper 139 reaches the fourth position, the magnet 125' is energized to close the line contacts 125, 125. When the calling subscriber operates his sender impulses are sent which break the circuit through the magnet 115, causing it to retract its armature. This momentarily breaks the circuit of magnet 123, but being slow to release it will maintain its armatures attracted. When the armature of magnet 115 is retracted, a circuit is formed from ground, armature and back contact of magnet 115, inner right armature and front contact of magnet 123, magnet 126, side-switch wiper 127 in first position, magnet 24 to battery and ground. Magnet 24 thereupon steps shaft 17 around to select the desired brush. Upon the cessation of the first set of impulses, magnet 115 remains energized and breaks this circuit at its back contact. Upon the first retraction of the armature of magnet 115 the magnet 126 was energized and remains energized during the sending of impulses, being a slow relay, but when its circuit is broken for a longer period of time it releases. By pulling up, magnet 126 closes a circuit through ground, its armature, side-switch wiper 128 in the first position, escape magnet 41, battery and ground. Magnet 41 pulls up and holds during the sending of the first set of impulses. At the end of the first set of impulses, magnet 126 releases and opens this last named circuit, causing magnet 41 to release and advance the side-switch wipers into second position.

During the sending of the second set of impulses by the calling subscriber, the following circuit is intermittently closed and opened from ground, armature and back contact 121 of magnet 115, inner right armature of magnet 123, magnet 126, side-switch wiper 127 in second position, magnet 12, battery and ground. Through this circuit the magnet 12 is now caused to operate and steps up shafts 4 and 17. At the end of the set of impulses magnet 41 advances the cams 45 and 46 to third position as before through the circuit through side-switch wiper 128.

Through side-switch wiper 129 in second position a new circuit is prepared from ground, outer right armature and back contact of magnet 123, wiper 129, armature 42, magnet 41, to ground. This circuit is introduced to cause an automatic action of the magnet 41 to move the cams 45 and 46 around to normal position and is put in at

this time so that if circuit conditions should cause magnet 115 to become permanently de-energized the mechanism would be automatically moved to normal position ready for another operation.

With the side switch in its third position relay 131 is energized over a circuit from ground, armature and front contact 122 of magnet 115, side-switch wiper 132 in third position, magnet 131 to battery and ground. Magnet 131 pulls up and locks itself over a circuit from ground, battery, magnet 131, its armature, side-switch wiper 133 in the third position, normal contact 134, to ground. As soon, however, as magnet 12 commences to operate and step up shaft 17, the ground on magnet 131 through normal contact 134 is removed by the opening of said contact and transferred to test brush 2 and this ground is maintained as long as the test brush engages test terminals of busy line. When magnet 131 is first energized by the movement of the side-switch wiper 132 to third position an automatic stepping circuit for magnet 12 is established from ground, inner right armature and front contact magnet 131, armature 11 of magnet 12, magnet 12, battery and ground. The automatic action of magnet 12 causes the brushes 2, to hunt out an idle line, the bar 9 having previously been released from shaft 4 as described heretofore. As soon as the brushes 2, contact with an idle line the ground or magnet 131 is removed and it deenergizes, breaking circuit for magnet 12 at its right contact, thus stopping magnet 12. Also when magnet 131 pulls up a circuit for magnet 41 is established from ground, outer right armature 135 of magnet 131, magnet 41, to battery and ground. Thus when magnet 131 de-energizes magnet 41 is caused to move the side-switch wipers to fourth position. In this position the two subscribers' lines are connected and the wipers remain in this position until conversation has ceased. All the magnets are in normal condition except 115, 123 and 125' which are pulled up. When conversation ceases, magnet 115 de-energizes, causing 123 to be deenergized and retract its armatures. Thus at the outer right armature of magnet 123 circuit for magnet 125' is broken, causing it to disconnect the lines at 125, 125, and at the back contact of the outer right armature a circuit is established through side-switch wiper 129 causing magnet 41 to automatically step around the cam disks 45 and 46. When the cam disk 46 reaches its seventh position it causes the release and restoration of the shafts and brushes as previously described and then is moved to eighth position. When the shafts reach their normal position, normal contact 136 is closed, which, because magnet 123 has retracted its armatures, establishes a circuit for magnet 41 from 130

ground, out of right armature of magnet 123, side-switch wiper 129 in eighth position, armature 42, magnet 41 to battery and ground, causing one more step of magnet 41 to cause the side-switch wipers to assume normal position 1. When the side-switch wiper 137 returns to normal position ground is taken off lead 124, which causes the release of the line finder in a well known manner. The parts of the mechanism shown but not described operate in substantially the same manner as set forth in my copending application above referred to.

What is claimed is:

1. In an automatic switch, a contact bank comprising terminal sets arranged in sections and groups, a brush-carrying shaft, an auxiliary shaft, means to operate said auxiliary shaft to control the selection of the desired section, means to operate said brush-carrying shaft and said auxiliary shaft simultaneously to control the selection of the desired group, and means to again operate said auxiliary shaft to control the selection of a desired terminal set.

2. In an automatic switch, a contact bank comprising terminal sets arranged in sections and groups, a brush-carrying shaft, an auxiliary shaft, means to rotate said auxiliary shaft to control the selection of a desired section, means to advance said brush-carrying shaft and said auxiliary shaft simultaneously in a longitudinal direction to control the selection of a desired group, and means to operate said auxiliary shaft in a longitudinal direction to control the selection of a desired terminal set.

3. In an automatic switch, the combination with a contact bank comprising terminal sets arranged in sections and groups, each section comprising a plurality of unit layers of multiple contacts, said layers being mounted in superimposed relation to each other, each layer forming a group of terminal sets, a brush-carrying shaft, an auxiliary shaft, means to operate said auxiliary shaft to control the selection of a desired section, means to operate said brush-carrying shaft and said auxiliary shaft simultaneously to control the selection of a desired group, and means to again operate said auxiliary shaft to control the selection of a desired terminal set in said group.

4. In an automatic switch, a contact bank comprising terminal sets arranged in sections and groups, each section comprising a plurality of superimposed layers of multiple contacts, each layer forming a group of terminal sets, a shaft, a plurality of brushes on said shaft serving said sections, an auxiliary shaft, means to operate said auxiliary shaft to control the selection of a desired brush, means to operate said brush-carrying shaft and said auxiliary shaft simultaneously to advance said brush to a desired

group and means to again operate said auxiliary shaft to move the selected brush in over the terminal sets of the selected group.

5. In an automatic switch, the combination with a contact bank comprising terminal sets arranged in sections and groups, each section comprising a plurality of unit layers of multiple contacts, each layer comprising a group of terminal sets, of a shaft, a plurality of brushes on said shaft serving said sections, an auxiliary shaft, means to rotate said auxiliary shaft to control the selection of a desired brush, means to advance said brush-carrying shaft and said auxiliary shaft simultaneously in a longitudinal direction to move the brush to a desired group, and means to operate said auxiliary shaft in a longitudinal direction to move said brush in over the terminal sets of the selected group.

6. An automatic switch comprising a contact bank having terminal sets arranged in levels, a shaft, a plurality of brush carriages carried by but capable of movement independently of said shaft, brush sets mounted on said carriages, an auxiliary shaft coöperating with said brush-carrying shaft, operating members carried by said auxiliary shaft, means for operating said auxiliary shaft to position one of said members in operative relation to a desired brush carriage, means for simultaneously advancing said brush carriages and said shafts to a desired level, and means for disengaging said shafts and for operating said auxiliary shaft to cause the selected brush carriage to be engaged and to advance its associated brush set over the terminal sets in the selected level.

7. An automatic switch comprising a contact bank having terminal sets arranged in levels, a hollow shaft having a series of slots in its wall, a plurality of brush carriages carried by but capable of movement independently of said shaft, brush sets mounted on said carriages, an auxiliary shaft movable within said hollow shaft, operating members on said auxiliary shaft, means for operating said auxiliary shaft to position one of said members opposite a slot in operative relation to a desired brush carriage, means for advancing said brush carriages and said shafts to a desired level, and means for disengaging said shafts and for operating said auxiliary shaft to cause the selected brush carriage to be engaged and to advance its associated brush set over the terminal sets in the selected level.

8. An automatic switch comprising a contact bank having terminal sets arranged in levels, a hollow shaft having a series of slots in its wall, a plurality of brush carriages carried by but capable of movement independently of said shaft, an auxiliary shaft movable within said hollow shaft, a series

- of slots in said auxiliary shaft, operating levers in said last mentioned slots; means for actuating said auxiliary shaft to position one of said levers opposite a slot in the wall 5 of said hollow shaft in operative relation to the desired brush carriage, means for stepping the brush carriages and said shafts up to the desired level, means for disengaging said shafts, means for operating said auxiliary shaft independently of said hollow shaft, and means for causing the selected operating lever to engage the desired brush carriage when the auxiliary shaft moves relatively to the hollow shaft.
- 10 9. An automatic switch comprising a contact bank having terminal sets arranged in levels, a hollow shaft having a series of slots in its wall, a plurality of brush carriages carried by but capable of movement independently of said shaft, an auxiliary shaft movable within said hollow shaft, a series of slots in said auxiliary shaft, an operating lever in each of said last mentioned slots, each operating lever adapted to coöperate with a 15 particular brush carriage, means for moving the auxiliary shaft with respect to the hollow shaft, and means on said hollow shaft to cause the selected operating lever to engage its brush carriage when such movement 20 takes place.
10. An automatic switching system comprising a contact bank having terminal sets arranged in levels, a longitudinally movable shaft, a plurality of sets of movable contacts 25 carried by said shaft, an auxiliary shaft co-operating with said movable contact-carry- 30 ing shaft, operating members on said shaft, means for operating the auxiliary shaft to position one of said members in operative relation to a desired set of movable contacts, 35 means for disengaging said shafts, and a single means for stepping the movable contacts and the shafts up to a desired level and for operating said auxiliary shaft after such disengagement to cause the selected set of 40 contacts to move in over the stationary contacts.
11. In an automatic switch, a shaft, a second shaft coöperating therewith, a ratchet wheel connected with said second 45 shaft for rotation therewith but arranged to permit relative longitudinal movement between the shaft and ratchet wheel, means for locking said ratchet wheel, and means on said first shaft to engage said locking means 50 and release the ratchet wheel when the first shaft moves toward the ratchet wheel.
12. In an automatic switch, a hollow shaft, a rod within said shaft, a ratchet wheel connected with said rod but not movable longitudinally therewith, a pivoted pawl engaging said ratchet wheel, said pawl having a shoulder rearwardly of the pivot point, and an arm on the lower end of said hollow shaft adapted to strike said rear 55 shoulder and release the pawl from the ratchet wheel when the hollow shaft approaches said ratchet wheel.

In witness whereof, I hereunto subscribe my name this 27th day of October A. D., 70 1917.

JOHN NEWBERRY REYNOLDS.
